UNITED STATES PATENT OFFICE.

WALLACE W. LONG, OF DETROIT, MICHIGAN.

GAME.

Application filed October 17, 1923. Serial No. 669,123.

To all whom it may concern:

Be it known that I, WALLACE W. LONG, a citizen of the United States, residing at Detroit, in the county of Wayne and State 5 of Michigan, have invented new and useful Improvements in Games, of which the following is a specification.

This invention relates to a game, the general object of the invention being to provide 10 a movable table carrying a chart and a base having pointers thereon for indicating certain characters or words on the chart, in the movement of the table, for answering questions and the like.

15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views, and in which:

Fig. 1 is a plan view of the device.

Fig. 2 is a side view thereof.

Fig. 3 is an end view.

30 Fig. 4 is a section on line 4—4 of Fig. 1.

Fig. 5 is a detail view of one of the legs of the table.

Fig. 6 is a view of the chart which is carried by the table.

35 In these views 1 indicates a base which has a smooth upper surface and which is of rectangular shape, as shown. A post 2 is placed at each side of the base, at the center thereof, these posts being inserted 40 in sockets 3 which are fixed in the base so that the posts can be removed when desired. The table 4 is also of rectangular shape but much smaller than the base and it is provided with the smooth metal feet 45 5 so that it can move about upon the base. This table carries the chart 6 which is divided by the lines 7 into the columns 8. The columns at the ends of the chart contain the letters of the alphabet and the numerals 1 to 9 and zero and these columns 50 also carry the black triangles 9 and the white substantially triangles 10 which are alternately arranged. Lines 11 lead from the apex of each dark triangle to a character or word in the second column from each end of the chart. The white triangles

are associated with the numerals and letters of the alphabet in the first columns. Words and phrases are placed in the other columns, excepting the center one which 60 contains the three circles 12, 13 and 14 and the words "Yes" and "No". The word "Yes" is arranged at the top of the column and the word "No" at the bottom thereof. The circle 12 contains the arrows 15 which point 65 in a clockwise direction and the words "Modus felix" meaning (In happy or agreeable mood). The circle 14 contains the arrows 16 which point in an anti-clockwise direction and the words "Modus gravis" 70 meaning (In grave or serious mood). The central circle may contain the name of the game.

The device is to be used by two persons, preferably male and female and they 75 are to place their finger tips lightly but firmly on the ends of the table. As the table moves about it will come in contact with either one of the posts 2 and if it strikes the post with one of the white triangles touching the post the letter of the alphabet or numeral opposite said triangle will be indicated. If it touches the post with one of the dark triangles touching the 80 post the word or character in the second column, opposite the triangle, will be indicated. If the post strikes this triangle twice the word in the next column will be indicated and if it strikes it three times the word in the fourth column will be indicated 85 and if it strikes it four times the word in the fifth column will be indicated. If the table moves in a rotary direction, indicated by the arrows 15 in circle 12, it will signify smiles or laughter according 90 to the rate of movement, a rotary movement according to the arrows in the circle 14 will signify gravity or anger; according to the rate of movement. Lengthwise movement will signify yes and no, respectively, 100 as indicated by the end arrows and the words "Yes" and "No".

Thus questions can be asked and answered by the device and fortunes told so that considerable amusement will be afforded by the 105 device.

What I claim is:

A device of the class described comprising a base, a post at each side thereof, means for removably supporting each post, a 110 table movably mounted on the base and a chart carried by the table, said chart being

divided into columns and having words and characters in the columns, the end columns having substantially triangular spaces of different colors therein, said substantially 5 triangular spaces being alternately arranged and are designed to indicate the words and characters in the columns when that part of the table carrying the substantially triangular spaces engages a post, the central

column carrying the words "Yes" and "No", 10 one at each end thereof, and a pair of circles, one for indicating rotary movement in one direction and the other rotary movement in the opposite direction.

In testimony whereof I affix my signature.

WALLACE W. LONG.
